UNITED STATES PATENT OFFICE

172,840

CHICKEN FRYER

Ralph R. Olswang, Scarsdale, N. Y.

Application March 23, 1954, Serial No. 29,668

Term of patent 14 years

(Cl. D44—1)

To all whom it may concern:

Be it known that I, Ralph R. Olswang, a citizen of the United States, residing in Scarsdale, in the county of Westchester, State of New York, have invented a new, original, and ornamental Design for a Chicken Fryer, of which the following is a specification, reference being had to the accompanying drawing, forming a part hereof, in which:

Fig. 1 is an exploded view in perspective of a chicken fryer, showing my new design; and

Fig. 2 is a side elevational view thereof.

I claim:

The ornamental design for a chicken fryer, as shown.
